United States Patent Office

Des. 216,022
Patented Nov. 18, 1969

216,022

SADDLE TREE

Carl J. Queen, 5300 New Peachtree Road,
Chamblee, Ga. 30005

Filed Oct. 31, 1968, Ser. No. 14,246

Term of patent 7 years

Int. Cl. D30—03

U.S. Cl. D30—20

FIG. 1

FIG. 2

FIG. 3

FIG.4

FIG. 5

FIG. 6

FIGURE 1 is a perspective view of a saddle tree embodying my new design;

FIGURE 2 is a top plan view thereof;

FIGURE 3 is a side elevational view thereof;

FIGURE 4 is a bottom plan view thereof;

FIGURE 5 is a front elevational view thereof; and

FIGURE 6 is a rear elevational view thereof.

I claim:

The ornamental design for a saddle tree, substantially as shown and described.
